Primary Examiner—Robert M. Spear
Attorney, Agent, or Firm—Jenkins & Gilchrist, P.C.[57] **CLAIM**

The ornamental design for a three-dimensional formed and perforated film having an oval-dot design therein, as shown and described.

DESCRIPTION

FIG. 1 is a top perspective view of a three-dimensional formed and perforated film having an oval-dot design therein showing my new design;

FIG. 2 is a top plan view thereof;

FIG. 3 is a front elevational view thereof, which is a mirror image of the rear side elevational view thereof;

FIG. 4 is a right side elevational view thereof, which is a mirror image of the left side elevational view thereof; and,

FIG. 5 is an enlarged cross-sectional view taken about the sectional lines 5—5 from FIG. 2.

The sides of the three-dimensional formed and perforated film having an oval-dot design therein have been shown broken away in FIGS. 1—5 to indicate indeterminate length. The surfaces or portions of the article not shown in the drawing or described in the specification form no part of the claimed design.
